UNITED STATES PATENT OFFICE.

PERRY S. BAUER, OF CHICAGO, ILLINOIS, ASSIGNOR TO BAUER & BLACK, OF CHICAGO,
ILLINOIS, A CORPORATION OF ILLINOIS.

FUMIGATOR.

1,003,393.

Specification of Letters Patent. Patented Sept. 12, 1911.

Application filed February 2, 1911. Serial No. 606,229.

To all whom it may concern:

Be it known that I, PERRY S. BAUER, a citizen of the United States, residing at Chicago, in the county of Cook and State 5 of Illinois, have invented new and useful Improvements in Fumigators, of which the following is a specification.

This invention relates to fumigators and has for its object, to provide an article which 10 can be placed upon the market containing a charge of volatile disinfectant and also a charge of combustible material to be employed for volatilizing the disinfectant, the device being so constructed and arranged 15 that both the charges will be protected against injury and sealed from the atmosphere until the device is used.

The invention will be best understood from the following description when taken 20 in connection with the accompanying drawings illustrating one preferred embodiment thereof.

On the drawings—Figure 1 is a longitudinal sectional view of a fumigator taken 25 on the line 1—1 of Fig. 3. Fig. 2 is a similar view showing the device ready for use; and Fig. 3 is a sectional elevation on the line 3—3 of Fig. 2.

Referring to the drawings 5 designates 30 a shell preferably cylindrical in form and composed of sheet-metal or other non-combustible material. A receptacle or container 6 is fitted within one of the open ends of the shell, an integral rib 7 being provided 35 on the wall of the shell to prevent the container from slipping too far into the shell, and adapted to contain a charge 8 of volatile disinfecting material in solid form. The charge may be composed of any preferred 40 disinfectant but preferably consists of a composition of solid character which, when heated, will give off formaldehyde vapor.

A cap 9 adapted to fit the end of the shell containing the charge of disinfectant 45 contains a mass or charge 10 of solid hydrocarbon such as paraffin and a wick 11 embedded in the charge, said wick being preferably formed of paper or other combustible material which will initiate the combustion of the charge of paraffin. An internal annular bead or rib 12 is provided in the cap to prevent the charge of combustible material 50 from dropping out when the cap is removed. A similar bead may be provided

in the container to insure the retention of 55 the charge of disinfecting material, if desired.

It will be observed from Fig. 1 that the cap fits tightly over the end of the disinfectant container and while the rib 13 limits the telescoping movement of the cap on the shell it permits the edges 14 of the receptacle and shell to enter the paraffin contained in the cap sufficiently to form an air-tight seal for the container. The advantages of 60 this hermetic sealing of the container will be obvious when it is remembered that the charge consists of a very volatile disinfectant which would be vaporized and lost to the atmosphere long before the device was 65 ever used if no effective sealing were provided. The device is marketed with the charges of disinfectant and combustible material already disposed in the container and the cap, respectively, and the cap being 70 affixed to the shell, as shown in Fig. 1, the article may be shipped, handled and exposed without danger of injury to either 75 of the contained charges and without the liability or possibility of the disinfectant becoming vaporized prior to the removal of the cap.

When the article is to be used the cap is removed from the container end of the shell and is applied to the opposite end, as shown 85 in Fig. 2. In this position of the parts the bottom of the container constitutes a crown-sheet which is exposed to the heat generated in the combustion chamber formed by the portion of the shell below the container 6. 90 The charge of combustible material may now be ignited by applying a flame to the wick, sufficient oxygen being supplied to the combustion chamber through the perforations 15 to properly support the combustion. The 95 heat generated in the combustion chamber causes the charge 8 to give off formaldehyde vapor which escapes from the open top of the container to the room to be disinfected.

The charges of vaporizable and combustible material are preferably so proportioned 100 that they will be consumed simultaneously, leaving only the non-combustible metallic parts which, being of comparatively inexpensive construction, may be discarded after 105 the device has been used.

The edges of the end of the shell opposite the container are preferably rolled inwardly

at 16 to present a smooth surface and obviate the liability of any one cutting themselves in handling the article.

Various changes in the size, shape and proportion of the various parts shown and described may be made, as will be apparent, without departing from the spirit of the invention.

I claim:

- 10 1. A fumigator comprising a shell, a disinfectant container carried thereby, and a cap containing a wick and a charge of combustible material normally forming a seal for said container, said cap being adapted to be disposed beneath the container for vaporizing the disinfectant therein.
- 15 2. A fumigator comprising a shell, a receptacle containing a charge of volatile disinfectant situated near one end of the shell, a cap containing a wick and a charge of combustible material adapted to fit over either end of said shell to form a seal for the disinfectant receptacle and to supply heat to said receptacle to vaporize said disinfectant, respectively.
- 20 3. A fumigator comprising a shell provided at one end with an open top receptacle containing a charge of volatile disinfectant, and a cap containing a wick and a charge of solid combustible material adapted to fit each end of the shell to form a seal for the disinfectant receptacle and to subsequently serve as a burner to heat said receptacle and vaporize the disinfectant contained therein.
- 25 4. A fumigator comprising a shell, a disinfectant receptacle arranged within said

shell adjacent one end thereof and containing a charge of volatile disinfecting material, and a cap containing a wick and a charge of combustible material in solid form adapted to fit both ends of said shell, said cap when fitted upon one end forming a seal for the disinfectant receptacle and when fitted over the other end serving as a burner to heat said receptacle and volatilize the disinfectant contained therein.

5. A fumigator comprising a shell carrying a charge of disinfecting material, and a cap containing a wick and a combustible charge consisting of a body of solidified hydrocarbon, said cap being adapted to fit either end of the shell, the end of the shell being embedded in the hydrocarbon when the cap is disposed over one end of the shell thereby forming a hermetic seal for the disinfectant contained in the shell, the cap when fitted upon the opposite end of the shell serving as a burner to heat the disinfectant and cause the same to be volatilized.

6. A fumigator comprising a shell having a charge of disinfecting material, and a cap carrying a charge of combustible material and a wick, said cap being adapted to fit one end of the shell to form a seal for said disinfecting material and to be detached therefrom and positioned beneath the other end of the shell for vaporizing said disinfecting material.
